UNITED STATES PATENT OFFICE.

CHRISTIAN BLOHM, OF ALTONA, PRUSSIA, GERMANY.

DEVICE FOR PUTTING ON BOOTS OR SHOES.

SPECIFICATION forming part of Letters Patent No. 312,321, dated February 17, 1885.

Application filed December 22, 1884. (No model)

To all whom it may concern:

Be it known that I, CHRISTIAN BLOHM, a subject of the Emperor of Germany, and a resident of Altona, in the Kingdom of Prussia and 5 German Empire, have invented certain new and useful Improvements in Implements for Putting on Boots or Shoes, of which the following is a specification.

My invention relates to improvements in 10 implements for putting on boots or shoes; and the objects of these improvements are, first, to facilitate the attaching of the boots or shoes to the implement and the disengaging from the same, and, second, to provide means for 15 adjusting the height of the suspending device with reference to the varying height of the boots or shoes. I attain these objects by the device illustrated in the accompanying drawings, in which—

20 Figure 1 is a perspective view; and Fig. 2, a side elevation, partly in section.

Similar letters refer to similar parts throughout the several views.

The rectangular or otherwise shaped frame 25 *a* is provided at opposite sides with vertical pegs *b*, of conical shape, whereon the straps of the boot or shoe are suspended in such a manner as to open the upper sufficiently for introducing the foot. By pushing down the foot 30 into the suspended boot or shoe the latter is put on correctly, and by withdrawing the foot from the interior of the frame the straps are disengaged easily from the pegs *b*, in consequence of their conical shape and their vertical 35 position. The supports of the frame *a* are com-

posed of two levers, *d* and *f*, hinged together by the bolt *c*. The lever *d* is hinged to the nut *h* by means of the bolt *i*, and the lever *f* to the nut *g* by the bolt *k*. Both nuts are actuated by means of a right and left hand screw, *e*, 40 resting in bearings *l* and *m*, fixed to the frame *a*. Thus the height of the frame *a* above the ground is adjusted in correspondence with the height of the boots or shoes.

Having thus fully described my invention, 45 what I desire to claim and secure by Letters Patent is—

1. A horizontal frame having legs or supports, and vertical pegs on opposite sides of a central opening, adapted to receive the straps 50 of a boot or shoe, substantially as and for the purpose set forth.

2. A vertically-adjustable horizontal open frame having legs or supports, and pegs adapted to receive the straps of a boot or shoe, substantially as and for the purpose set forth. 55

3. In implements for putting on boots or shoes, the combination of the frame *a* with the screw *e*, nuts *h* and *g*, and levers *d* and *f*, 60 hinged together by means of the bolt *c*, substantially as and for the purpose specified.

In testimony that I claim the foregoing as my invention I have signed my name, in presence of two witnesses, this 2d day of December, 1884.

CHRISTIAN BLOHM.
